Attorney.

UNITED STATES PATENT OFFICE

146,659

DESIGN FOR A HYDROCYCLE

Erich Jaeger, La Falda, Argentina, assignor to
Otto F. Rien, Yeadon, Pa.

Application January 22, 1946, Serial No. 125,838

Term of patent 14 years

(Cl. D71—1)

To all whom it may concern:

Be it known that I, Erich Jaeger, a citizen of Argentina, residing at La Falda, Argentina, have invented a new, original, and ornamental Design for a Hydrocycle, of which the following is a specification, reference being had to the accompanying drawing, forming part thereof.

Figure 1 is a top plan view of the hydrocycle embodying my novel design.

Fig. 2 is a side elevational view

Fig. 3 is a front elevational view, and

Fig. 4 is a rear elevational view thereof.

I claim:

The ornamental design for a hydrocycle, as shown.

ERICH JAEGER.
